(57) **CLAIM**

We claim the ornamental design for a vacuum cleaner nozzle attachment, as shown and described.

DESCRIPTION

FIG. 1 is a front perspective view of a vacuum cleaner nozzle attachment of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a front perspective view thereof shown in an environmental use.

The broken line showing of vacuum cleaner nozzle attachment is included for the purpose of illustrating environment and forms no part of the claimed design.
